UNITED STATES PATENT OFFICE.

REINHOLD HERMAN, OF CRAFTON, PENNSYLVANIA.

DESIGN FOR A BRACKET FOR ELECTRIC WIRES.

SPECIFICATION forming part of Design No. 19,190, dated July 2, 1889.

Application filed June 7, 1889. Serial No. 313,506. Term of patent 14 years.

To all whom it may concern:

Be it known that I, REINHOLD HERMAN, a citizen of the United States, residing at Crafton, in the county of Allegheny and State of Pennsylvania, have invented and produced 5 a certain new and original Design for Brackets for Electric Wires, of which the following is a specification.

The invention described herein relates to a 10 certain new and original design for brackets for electric wires.

In the accompanying drawings, forming a 15 part of this specification, Figure 1 is a view in side elevation of a bracket embodying my design; and Fig. 2 is a sectional view on the line $x-x$, Fig. 1.

Two arms 2, consisting of radially-arranged ribs or webs 3, extend radially and in oppo-

site directions from the upper portion of the stem 1. The outer portions 4 of these arms 20 form an angle with the main portions thereof, and the ends of the portions 4 have a spiral rib, as at 5.

The leading or characteristic features of the design are arms, star-shaped in cross-section, 25 radiating from a common stem and having angularly-arranged outer portions.

I claim herein as my invention—

The design for a bracket for electric wires, 30 as herein shown and described.

In testimony whereof I have hereunto set my hand.

REINHOLD HERMAN.

Witnesses:

DARWIN S. WOLCOTT,
R. H. WHITTLESEY.
